UNITED STATES PATENT OFFICE.

ARCHIMIDES S. KEEVER, OF COLUMBUS, OHIO.

TOY.

SPECIFICATION forming part of Letters Patent No. 669,700, dated March 12, 1901.

Application filed July 20, 1900. Serial No. 24,253. (No model.)

To all whom it may concern:

Be it known that I, ARCHIMIDES S. KEEVER, a citizen of the United States, residing at Columbus, in the county of Franklin and State 5 of Ohio, have invented a certain new and useful Improvement in Toys, of which the following is a specification.

My invention relates to an improvement of toys; and the objects of my invention are 10 to provide an inexpensive and attractive toy which is designed to impart a buzzing sound when properly manipulated and to produce certain improvements in construction and arrangement of the parts of said toy, which will 15 be more fully pointed out hereinafter. These objects I accomplish in the manner illustrated in the accompanying drawings, in which—

Figure 1 is a face view of the toy. Fig. 2 is a rear elevation thereof, and Fig. 3 is a sectional view on line $\alpha\alpha$ of Fig. 2.

Similar numerals refer to similar parts throughout the several views.

In carrying out my invention I construct my improved toy in the form of a fly, of which 25 1 represents the oblong body, which, as indicated in Fig. 3 of the drawings, is of sufficient thickness to impart a desirable rigidity thereto. On its rear face, at its ends, the body 1 is reinforced or enlarged rearwardly, as indicated at 2, and said body is provided with an oblong opening 2^a. Secured to the front face of the body 1 is a plate 3, having in its lower portion the form of said body and having rising therefrom wing-shaped projections 35 4. The outer face of this plate is suitably printed or decorated to imitate the body and wings of a fly.

5 represents a rubber band, which is stretched horizontally about and made to embrace the ends of the fly-body, said band passing over the enlargements 2 and being detachable. Connected with the head of the fly is one end of a cord 6 of suitable length. As indicated at 7, I form the ends of the body 45 of the fly with a desirable number of notches, with the desired ones of which the rubber band 5 may be made to engage, for the pur-

pose hereinafter set forth. Over the opening 2^a in the body I secure a strip of rubber 8.

The manner of manipulating the toy to produce the desired result consists in grasping the outer end of the cord or string 6 and whirling the body of the toy rapidly through the air. This continued rapid circular motion of the toy-body results through contact 55 of the air with that portion of the rubber band which bridges the enlargements 2 and the strip of rubber 8, which bridges the opening 2^a in imparting a buzzing sound similar to that of a fly. It has been found that by increasing or decreasing the tension on the rubber band, which may be accomplished by slightly changing the angle at which it extends across the body of the fly and engaging the band with different notches 7, a perceptible change in the tone of the buzzing 60 may be produced.

It will be seen that a toy constructed as above described may be produced at an exceedingly low cost of manufacture and that 70 the same may be produced in a neat and attractive form and the face of the plate 3 printed in such colors as may be desirable.

Having now fully described my invention, what I claim, and desire to secure by Letters 75 Patent, is—

1. In a toy, the combination with the body 1 having raised and notched end portions and projecting wing portions, of an elastic band bridging the ends of said raised portions and 80 a cord connected at one end with said body, substantially as specified.

2. In a toy, the combination with the body 1 having raised end portions and an opening formed in said body, of an elastic band 85 bridging the raised end portions of said body and a strip crossing the opening in said body and a cord connected at one end with the body, substantially as specified.

ARCHIMIDES S. KEEVER.

In presence of—

W. L. MORROW,
A. L. PHELPS.
